UNITED STATES PATENT OFFICE.

ROBERT H. SIPES, OF UNION CITY, INDIANA.

DESIGN FOR A GRAVE-COVER.

SPECIFICATION forming part of Design No. 12,923, dated May 9, 1882.

Application filed February 7, 1882. Term of patent 14 years.

To all whom it may concern:

Be it known that I, ROBERT H. SIPES, a citizen of the United States, residing at Union City, in the county of Randolph and State of Indiana, have invented and produced a new and original Design for Grave-Covers, of which the following is a specification, reference being had thereto to the accompanying drawing.

10 My invention relates to a new and original design for grave guards or covers, the form and construction of which will be hereinafter more fully set forth and described.

15 The drawing represents a perspective view of my grave-guard.

This invention relates to metal grave-guards; and it consists in a metal plate or frame of the form and shape shown in the drawing, and of dimensions according to the size of grave 20 to be protected. It has an elongated opening in its face, the ends of which may be either rounding, as shown in the drawing, or square, with a raised flange around its sides. Around the outer sides of the guard, projecting down- 25 ward and slightly outward, except where crossing the head, where it is perpendicular, are ornamental flanges. Near the edges of the upper face of the guard are placed a line of ornamental reliefs of harmonious design and

effect, as shown. The head of the guards is 30 made at right angles with a line drawn through the center of the guard. The guard is provided with supports or legs, usually four in number, and placed at the ends of and inside the border flanges of the guard. The supports 35 are broad in the direction of the length of the guard.

The guard may be bronzed, galvanized, painted and sanded, or painted any color desired.

40 What I claim is—

A cast-metal grave-guard formed into a flat plate having an elongated central opening in its face, the outer edges bent downwardly and provided with supports under each of its corners, and an upwardly-projecting ornamental flange around its upper face, and the face of the head end perpendicular and at right angles with a line drawn through the center of the guard, substantially as and for the purposes 45 50 set forth and described.

In testimony whereof I hereto affix my signature in presence of two witnesses.

ROBERT H. SIPES.
